UNITED STATES PATENT OFFICE.

EFFINGHAM L. POLLARD, OF DOBBS FERRY, NEW YORK.

PASTE-DISTRIBUTER.

1,117,238.

Specification of Letters Patent. Patented Nov. 17, 1914.

Application filed July 1, 1911. Serial No. 636,395.

To all whom it may concern:

Be it known that I, EFFINGHAM L. POLLARD, a citizen of the United States, and resident of the town of Dobbs Ferry, county 5 of Westchester, and State of New York, have invented certain new and useful Improvements in Paste-Distributors, of which the following is a specification.

This invention relates to a means for distributing any pasty substance from a central reservoir or supply chamber to a greater or less number of outlets where it is to be used.

Many excellent lubricants are in paste 15 form and it is often desirable to lubricate by means of a paste in places where an ordinary paste or grease cup cannot be conveniently used, therefore I have designed a means for furnishing through a small tube 20 the desirable quantity of paste, and I have devised a means for controlling the amount of the supply from a position close to the reservoir.

Another use for my system of distribution is in supplying soap for use in public lavatories. A supply of the pasty soap is retained in the reservoir under pressure, and a tube leading from the reservoir and having an outlet adjacent to each of the 30 hand bowls is continually subjected to the pressure of the reservoir. A peculiarly constructed valve is connected to the tube and supplies an outlet for the soap at each of the basins. In this manner I construct a highly 35 satisfactory and perfectly sanitary soap receptacle, particularly desirable for use in hotels, theaters, sleeping cars and in any other place where a large number of people make use of the washing facilities.

40 The following is what I consider the best means of carrying out this invention.

The accompanying drawings form a part of this specification, in which:

Figure 1 is a view in elevation, it shows 45 the complete system in operation as a soap retainer. The remaining views are on a larger scale. Fig. 2 is a central vertical section, through the reservoir and one of the valves to be used in conjunction therewith. 50 Fig. 3 shows two of the nozzles that may be used on the discharge nipple of the valve.

Similar reference numerals indicate like parts in all the figures where they appear.

One of the principal features of my invention is the reservoir or container. It is

into this that the soap or grease in the form of plastic or viscos mass is placed.

The container may be constructed of sheet metal and I prefer that if so made, it shall be carefully enameled, or it may be constructed of clear glass or porcelain. It consists of a body member 1, cupped shape and having a perforation or nipple 2, formed integral with or secured into the center of the bottom. The top of the member 1 is open 60 and the inner walls of the member should be smooth. Formed upon the exterior of the member 1, and at a convenient height, is a ridge 3 which serves to support the member in a proper holder which will be described 65 later, and surrounding the top edge of the member 1. I have produced a screw-thread 4, for the reception of a closing cap 5. The closing cap 5 is also provided with screw-threads and is constructed to fit snugly 70 upon the screw-thread 4. The cap 5 is also cupped shape though cupped in the direction opposite to the member 1. A central perforation is produced in the cap 5 and a stuffing-box is screw-threaded into the 75 central perforation. This stuffing-box 6 serves a double function, as a water tight passage for a piston rod 7, and as an adjusting means for a cone shaped spring 8, both of which will be described later. A nipple 80 or nozzle 9, passes through the cap 5. This nipple is the pressure inlet and it is intended to be connected to a convenient source to water supply under pressure. If the pressure of the water is found to be too 85 great, a regulating or reducing valve may be inserted into the water pressure line, though if such a valve be inserted I prefer that it be quite near the container as it may be found desirable to vary the pressure 90 upon the contents of the container from time to time.

Within the container a piston 10 operates. This piston may be of any desirable construction, though I have constructed it of a 100 solid block of a diameter to fit freely within the container. The piston rod 7, screw-threaded into a centrally disposed perforation in the piston 10 and passing through the stuffing box 6, retains the piston in alignment. Near the top of the piston, I have produced a groove 11, and into this groove I insert a suitable packing ring 12. The lower end of the piston 10, I turn to a 105 slightly smaller diameter than the upper 110

end as is shown at 13, and I place a cup-leather 14 over this smaller part and secure it there by means of a screw 15 and washer 16. It will be seen from this construction 5 that upon removing the cap 5, the piston 10 and the parts thereof are also removed, the container can then be nearly filled with pasty soap or grease and the cap and piston returned to position. Before doing this 10 however the water supply should be totally shut off and the container drained of whatever water it may hold. When the cap and piston are returned to operable position it will be found that the spring 8 will urge 15 the piston downward with considerable strength, even without the water supply. It will be seen therefore that I have provided two means for moving the paste each operating independently of the other, and under 20 certain conditions either of these means may be depended upon to serve alone.

Arranged low down on the side of the member 1 I have placed a pet-cock 17 for draining the container, after the water 25 pressure has been shut off and before the cap 5 has been removed for refilling.

In Fig. 1, I have shown the bracket or support for the container. It consists of a ring 18, supported by a wall bracket or foot 30 20, the container is passed into this ring before the permanent connections are made.

Connected to the nipple 2, is the distributing pipe 21, which may continue for any desired extent. The outlets from this pipe 35 are each controlled by a peculiarly constructed valve 22, shown in detail in Fig. 2. This valve consists of a body 23, which may be a casting and which is provided with an inlet passage 24 and an outlet passage 25 arranged diametrically opposite each other and at about mid-length of the body 23. The lower end of the valve body is provided 40 with a screw-threaded closing cap 26 and the upper end, which is somewhat contracted 45 and is closed by means of the stuffing box and guide 27. Arranged within the body and fitting snugly and rotatable therein is the valve member 28 having a liberal transverse passage 29 arranged to register with 50 the inlet and outlet passages through the body of the valve. The upwardly extending valve stem 30 carries a hand-wheel or button 31, and I prefer that this button be carefully enameled so as to receive instructions 55 as to the operation of the valve. Inward

projections 32, which may be formed integral with the valve body, support a spider 33, which may be secured upon the projections 32 by means of the pins or screws. The spider 33 serves as a guiding means for 60 a second projection 35 formed in one with the valve body, and also serves as a means for retaining one end of a spring 36. The other end of the spring is passed into a hole 37, in the projection 35. The outlet passage 65 25 may be provided with a delivery nozzle 40, shaped to fit snugly upon the end of the passage or nipple 25, and provided with a perforation 41 adapted to deliver the material in any desired shape. 70

The operation of this device is simple, the container having been placed in position and filled with the pasty material, the water pressure may be turned on, and when it is desirable to draw a quantity of the paste the hand may be placed under the nozzle 40 and the button or wheel 31 turned to the right, when a sufficient quantity of paste has been received, releasing the button 31 allows the spring 36 to close the valve. It is not necessary to turn off the water pressure or to perform any other operation for the container may remain entirely without attention until more of the paste is required. If the device is used for lubricating purposes 85 the spring 36 may or may not be omitted, if omitted the valve is controlled entirely by hand and may deliver a quantity of paste periodically or continuously.

Modifications may be made within the 90 scope of the appended claims without departing from the principle or sacrificing the advantages of this invention.

Having carefully and fully described my invention what I claim and desire to secure 95 by Letters Patent is:—

The combination with a lavatory of a soap container secured adjacent thereto, a spring within said container means for connecting a water supply to said soap container, and a semi-cylindrical piston adapted to be operated by said water supply and said spring for discharging the soap from said container as herein specified. 100

Signed at New York city, N. Y., this 24th 105 day of June 1911.

EFFINGHAM L. POLLARD.
